STAND FOR A FIREPLACE MATCH BOX

Carl-Erik Hagberg, Stockholm, Sweden, assignor to
Svenska Tandsticksbolagets Forsaljningsaktiebolag,
Stockholm, Sweden

Filed Apr. 8, 1974, Ser. No. 458,577

Claims priority, application Sweden Oct. 15, 1973

Term of patent 14 years

Int. Cl. D27—99

U.S. Cl. D27—31

The figure is a perspective view of a stand for a fireplace match box.

The two leg members not completely shown are the same in the shape as the leg completely shown while the two undisclosed vertical faces of the stand are plain and unornamented.

I claim:

The ornamental design for a stand for a fireplace match box, as shown and described.
